[57] CLAIM

The ornamental design for a stabilizer, as shown and described.

DESCRIPTION

FIG. 1 is a front elevational view of a stabilizer, showing a typical embodiment of my new design.

FIG. 2 is a left side elevational view.

FIG. 3 is a right side elevational view.

FIG. 4 is a top view.

FIG. 5 is a bottom view; and,

FIG. 6 is a front elevational view with the top box pushed into the bottom box.

The appearance of the rear is the same as the front.
